UNITED STATES PATENT OFFICE.

HENRY L. PITMAN, OF EAST ORANGE, NEW JERSEY, ASSIGNOR TO UNDERWOOD COMPUTING MACHINE COMPANY, OF NEW YORK, N. Y., A CORPORATION OF NEW YORK.

COMBINED TYPEWRITING AND COMPUTING MACHINE.

1,386,653.

Specification of Letters Patent.

Patented Aug. 9, 1921.

Application filed January 17, 1918. Serial No. 212,213.

To all whom it may concern:

Be it known that I, HENRY L. PITMAN, a citizen of the United States, residing in East Orange, in the county of Essex and 5 State of New Jersey, have invented certain new and useful Improvements in Combined Typewriting and Computing Machines, of which the following is a specification.

This invention relates to combined typewriting and computing machines, and more particularly to machines provided with means for obtaining the cross-total of numbers typewritten in a single line in different columns on the work-sheet.

15 This invention is illustrated in connection with the improvements disclosed in my co-pending applications No. 198,375, filed October 25, 1917 (now Patent No. 1,350,387, dated Aug. 24, 1920), and No. 24,390, filed 20 April 28, 1915 (now Patent No. 1,308,506, dated July 1, 1919).

In said application No. 198,375, the cross-totalizer is arranged to alternately travel with the typewriter carriage and return independently thereof repeatedly during each run of the carriage. For this purpose, tappets or dogs provided on the typewriter carriage pick up said cross-totalizer successively at different points in the run of the 25 typewriter carriage, and cause said cross-totalizer to move step-by-step with the typewriter carriage through the computing zone. When the typewriter carriage steps out of a computing zone, the cross-totalizer is 30 dropped or released from the carriage and returned to normal position, ready to be picked up by the next tappet on the typewriter carriage.

In practice it is often necessary to set 40 back the typewriter carriage for making corrections in the same line of writing and for other purposes. Sometimes this is accomplished by the hand of the operator pressing the carriage directly to the left; but in 45 many cases it is accomplished by the use of a back-space key, the depression of which sets the carriage back a single letter-space. Repeated operation of the key will set the carriage back two or more letter-spaces.

50 In setting back the carriage, it may sometimes be the case that the carriage is standing beyond the computing zone, and its backward or leftward movement will carry it into such zone. Such leftward movement,

as just explained, may be accomplished by 55 the back-space key or otherwise; the carriage coming to rest within the computing zone. One of the main features of the invention relates to the operation of parts as the carriage is backed into a computing 60 zone, particularly various parts of the computing mechanism.

The typewriter carriage and the cross-totalizer have a certain denominational relationship with each other. This relationship is determined by the position of the tappet carried on the typewriter carriage. This relationship is temporarily broken, however, when the typewriter carriage passes out of a computing zone; and in said 70 application No. 198,375 provision was made whereby the back-space key for the typewriter carriage could also reset the cross-totalizer accordingly; or in other words, the operation of the back-space key to set back 75 the typewriter carriage into a computing zone, also moved the cross-totalizer (with its associated parts) to reestablish the former denominational relationship between the typewriter carriage and the cross-totalizer. 80

The back-space key is not only used for back-spacing the carriage into the computing zone, but may also be used for back-spacing the carriage at any other place during its traverse. The connection between the back-space key and the cross-totalizer, in said pending application, is such that any actuation of the back-space key will move the cross-totalizer, whether the typewriter carriage is in a computing zone or not. 85

For the purpose of relieving the back-space key of this unnecessary operation of the cross-totalizer, except when actually required, the present invention provides a normally-ineffective connection between the back-space key and the cross-totalizer. This normally-ineffective connection is moved to effective position only when the typewriter 100 carriage is about to be back-spaced into a computing zone.

When the denominational relationship between the typewriter carriage and the totalizer is reestablished, the connection between the back-space key and the cross-totalizer is again made ineffective, so that subsequent operations of the back-space key 105

while the typewriter carriage is in the computing zone, will not operate the cross-totalizer.

For these purposes, the connection between the back-space key and the cross-totalizer may be shifted from effective to ineffective position by means of a feeler or intermediate element that is arranged to be engaged by connections from the cross-totalizer, so that, when the cross-totalizer and its connections are in normal positions, said feeler will be in position to make said connection effective as the backwardly traveling typewriter carriage approaches the computing zone. The typewriter carriage may control the feeler through a cam arranged to be engaged by the tappet on said carriage. This cam may be engaged by the typewriter carriage when the latter is a short distance from the computing zone.

From this it will be seen that the connections between the cross-totalizer and the back-space mechanism are controlled jointly, dependent upon the position of the typewriter carriage with relation to the computing zone, and upon the position of the connections from the cross-totalizer with relation to the tappet on the typewriter carriage.

The present invention also provides improved means whereby the numeral keys of the typewriting machine will be locked if the typewriter carriage is moved back into a computing zone by hand without being moved back sufficiently to reestablish its denominational relation with the cross-totalizer. This locking of the numeral keys forces the operator either to operate the back-space key, or to move the typewriter carriage sufficiently back to cause the cross-totalizer to connect to the typewriter carriage, and thus reestablish the proper denominational relationship between the two. This locking mechanism is under the joint control of the feeler and the typewriter carriage, so that it will only lock the numeral keys when the typewriter carriage is in the computing zone and the denominational relationship between the cross-totalizer and the carriage is not established.

The present invention also provides an improved train of connections between the tappet on the typewriter carriage and the cross-totalizer.

Other features and advantages will hereinafter appear.

In the accompanying drawings,

Figure 1 is a side view of the machine with parts broken away to show the interior structure.

Fig. 2 is a skeleton perspective view of the machine, looking from the other side, and showing the train of mechanism connecting the typewriter carriage and the cross-computer carriage. This figure also shows the

back-spacing mechanism for the typewriter carriage and a connection to the back-spacer key, which may be controlled by the typewriter carriage to render it effective or ineffective for repositioning the cross-totalizer denominational and relatively to the typewriter carriage.

Fig. 3 is a rear view in elevation, partly broken away, to show the means for locking the numeral keys when the typewriter carriage is backed into a computing zone without the aid of the back-spacer key. This figure also shows the train of links and levers forming the connection from the cross-computer carriage to the pick-up bar engaging with the pick-up dogs on the typewriter carriage. The typewriter carriage is shown as passing through a computing zone, and the cross-computer carriage with its totalizer traveling therewith.

Fig. 4 is a detail view, with the pick-up bar and the parts connected thereto in their normal position; the carriage approaching a computing zone, with the pick-up bar ready to be caught by the movement of the pick-up dog corresponding to the position, on the typewriter carriage, of the next totalizer to enter the computing zone.

Fig. 5 is a view similar to Fig. 4, showing the cross-computer carriage returned to its normal position, due to the release of the pick-up bar from the pick-up dog, immediately after the movement of the typewriter carriage out of the computing zone. This figure also shows the numeral-key lock, which is actuated by the pick-up bar, as rendered effective, and further shows the thrust bar, which forms part of the connection from the back-spacer key to the cross-totalizer, as moved to its effective position, so that it may, by the depression of the back-spacer key, reconnect the pick-up hook with the previously-engaged pick-up dog, to reposition the cross-totalizer.

Fig. 6 is a view similar to Fig. 5, except that the back-spacer key is in its actuated position, and showing the parts actuated thereby to reconnect the pick-up bar with the pick-up dog.

Fig. 7 is a detail section, taken on line 7-7 of Fig. 5, and looking in the direction of the arrows at said line, showing the relative arrangement of the pick-up bar, and how it engages with a fixed bracket to prevent it from swinging when it is in its normal position.

Fig. 8 is a sectional rear view, taken on the line 8-8 of Fig. 7, and looking in the direction of the arrows at said line.

Fig. 9 is a perspective view, showing the swinging lever comprising a shoe, which is actuated, when any one of the pick-up dogs passes through the computing zone, to raise the pivoted intermediate lever thereon to an effective position to be actuated by the pick-

up bar to render the key-locking mechanism and repositioning connection effective.

I have shown my invention as applied to an Underwood machine, in which alphabet 5 keys 10 and numeral keys 11, when depressed, swing key-levers 12 to rock bell-cranks 13 about a fulcrum rod 14, to swing type-bars 15 upwardly and rearwardly about a fulcrum 16, to cause types 17 to strike 10 against the front side of a rotatable platen 18. The platen 18 is rotatably mounted for line-spacing movements on a carriage 19, which travels back and forth on a front rail 20 and a back rail 21 for letter-feeding 15 movements.

For its letter-feeding movements, the carriage 19 is provided with a rack-bar 22, which meshes with a pinion 23 to rotate the latter. The pinion 23 is connected to rotate 20 an escapement wheel 24 by the usual one-way acting pawls 25. The escapement wheel 24 is provided with teeth 26, which coöperate with a loose dog 27 and a fixed dog 28 on a dog-rocker 29, when the latter 25 is vibrated by a universal bar 30, engaged by heels 31 of the type-bars 15 when the latter approach the printing point. The upper end of the dog-rocker is returned to its forward or normal position by the usual 30 springs (not shown).

The carriage 19 may be moved to bring any denominational position of a column on the platen to the printing point. To do this there is provided a series of tabulator 35 keys 32, as in the Underwood machine, which, when depressed, move plungers 33 against the tension of return springs 34, to bring the upper ends thereof into the path of effectively-set column-stops 35 on a stop-bar 36 secured to the typewriter carriage by a bracket 37. The usual rack-releasing means (not shown in the drawings) may be actuated by any one of the plungers 33 to effect the releasing of the carriage by raising the rack 22 out of engagement with the escapement pinion 23 at the proper time. The usual spring drum 37^a, Fig. 3, after the release of the carriage, moves the carriage 40 on its rails to the left until it is arrested by one of the effective column-stops coming 45 into engagement with the projected plunger. The tabulator key is then permitted to return to normal position, thus effecting a re-engagement between the feed rack 22 and pinion 23.

A back-spacer mechanism is provided for the typewriter carriage 19, which may be like that disclosed in the patent to Helmond No. 930,962, dated August 10, 1909, and may 50 comprise a back-spacer key 38, which, when depressed, rocks a shaft 39 to swing the forward end of an arm 40, located near the center of the machine, downwardly against the tension of a spring 41. This movement 55 of the arm 40 pulls downwardly on a con-

necting link 42 to swing a back-spacer pawl 43 into engagement with the teeth on the feed rack 22, by swinging it about a pivot 44 of an arm 45, upon which the pawl is supported at 46. After the pawl 43 is 70 brought into engagement with the teeth of the feed rack 22, it is arrested against further pivotal movement in this direction by the upper end of the arm 45 striking the rack 22, when a continued movement of the 75 connecting link 42 becomes effective to swing the pawl 43 in another direction about its pivot 46, to draw the carriage back from left to right, thus back-spacing the carriage one letter-space position. A spring 47 re- 80 turns the back-spacer pawl 43 to its normal position relatively to the arm 45, where it is arrested by a stop 48.

The computing mechanism may be similar to that shown in my co-pending application, Serial No. 24,390, herein referred to. Each numeral key may comprise a cam 50, by which a common indexing element (not shown in the drawings, but clearly described in my co-pending application) may be 85 moved through angular distances varying in values from 1 to 9 due to the different shapes of the cams 50 on the different numeral keys. These movements of the indexing element may be transmitted to a master wheel 52 to 90 rotate the latter through various angular distances corresponding to the value of the depressed numeral key. The master wheel 52 is so positioned that its movements may be transmitted to any one of a plurality of 95 column or footing totalizers 51; the master wheel engaging with a series of computing wheels 53, which transfer the values to a series of dial wheels 54 contained within 100 each totalizer. The totalizers 51 are mounted 105 for traveling movement relative to the master wheel 52, so that the computing wheels may be brought into coöperative relation successively with the master wheel as the typewriter carriage passes through a 110 computing zone. The totalizers may be adjustably secured to a supporting bar or computer carriage 56 connected to the typewriter carriage 19 to travel therewith, by 115 arms 57 and may be guided in its traveling movement by a rail 58.

The depression of a numeral key 11 while another numeral key is active is prevented by suitable locking means to avoid a mal-action of the computing mechanism. For this purpose, each key lever has pivoted thereon a pendent link 59, provided with a rearward extension 60, which, when its associated key 11 is depressed, is forced between a pair of pivoted pawls 61 to spread them, thereby moving the pawls associated with the other keys to an effective position to prevent the entrance therebetween of the rearward projections associated therewith. The series of locking pawls associated with 120 125 130

all of the numeral keys are pivotally supported at 62 on a plate 63, and are suspended between two studs 64 with an amount of play of the pawls between the studs 64 substantially equal to the thickness of one of the rearward projections 60; thus, by the depression of any one of the numeral keys, this play of the locking pawls is taken up to prevent the depression of another key before the return of the actuated key. The pendent links 59 are guided at their lower ends in a slot 63^a in a cross-bar 63^b to which the plate 63 is secured.

In addition to the column-computing unit comprising the master wheel 52, which may be a relatively-fixed element, and the totalizer 51, preferably a traveling element, there is also provided a cross-computing unit having a similar relatively-fixed element and a traveling element. To effect the cross-computing of numbers written in several columns, there is provided in the cross-computing unit a second master wheel or relatively-fixed element 66, which may be connected to the master wheel 52 to be driven therewith in a manner similar to that disclosed in my co-pending application, Serial No. 186,098, filed August 14, 1917 (now Patent No. 1,345,460, dated July 6, 1920), which may comprise a suitable train of mechanism extending from the master wheel 52, having a horizontal shaft 67, which, through bevel gears 68 and 69, drives a vertical shaft 70, which, in turn, by means of bevel gears 71 and 72 drives a shaft 73, which may be connected to drive the master wheel 66. These movements of the master wheel 66 may be transferred to a cross-totalizer or traveling element 74, through the intermediary of a series of computing wheels 75, to a series of dial wheels 76 contained within the cross-totalizer. The cross-totalizer 74 may be adjustably mounted on a supporting bar or cross-computer carriage 77, which may be intermittently connected (in a manner which will be presently described) to move in synchronism with the typewriter carriage 19 and the computer carriage 56 when the totalizers 51 pass through a computing zone. To guide the cross-computer carriage or sub-carriage 77 in its traveling movement, a suitable guide rail 78 may be provided.

To intermittently pick up the cross-totalizer 74 so that it may travel through a computing zone simultaneously with any one of the footing totalizers, there is provided a series of adjustable elements or pick-up dogs 80 on a bar 81, secured to the bracket 37 of the typewriter carriage. The pick-up dogs or elements 80 in construction are similar to the column-stops 35. Both column-stops and pick-up dogs may be key-set, as shown in my co-pending application, Serial No. 198,375. Each of the said pick-up dogs 80

engages with the projection 82^a on the pick-up bar 82 when the corresponding totalizer 51 enters a computing zone; thereby connecting the cross-totalizer carriage with the typewriter carriage.

In the present invention, during the passage of a totalizer 51 through the computing zone, the pick-up element or bar 82, which forms part of a train of mechanism extending between the typewriter or main carriage and the cross-totalizer or sub-carriage, is drawn from its normal position (Fig. 4) to rock a bell-crank or rock-arm 83 about its pivot 84, secured to the machine frame in any convenient manner. This causes a laterally-projecting arm 85 of the bell-crank 83, to move downwardly a thrust link 86, to swing an arm 87 and rock a shaft 88 conveniently supported on the machine frame. The rocking of the shaft 88 causes an arm 89 mounted at its forward end to draw on a link 90 and move against the tension of a return spring 91. The link 90 is pivotally connected at 92 to the cross-totalizer carriage 77, so that the latter is moved with the said link, and thus the cross-totalizer 74 moves in synchronism with the footing totalizer 51.

The pick-up bar 82 normally occupies the position in Figs. 4 and 7, where it is held slightly depressed by an offset 93 thereon which underlies a portion 94 of a fixed bracket 95. During the primary advancing movement of the pick-up bar, the offset 93 moves out of engagement with the portion 94 to allow a spring-actuated lever 97 to swing the pick-up bar about its pivot until a pin 96 on the pick-up bar strikes the upper side of a slot 95^a formed in the bracket 95. This swinging movement of the pick-up bar effects a better connection between the pick-up bar and the pick-up dog, by means of a slot 98 in the pick-up bar 82. Thus, the pick-up bar 82 is positively connected to the pick-up dog against relative movement in either direction while the corresponding totalizer passes through a computing zone. The pick-up bar 82 is released from the pick-up dog 80, after writing the last digit in a computing zone, by the pin 96 engaging with a cam 96^a on fixed bracket 95, which swings the pick-up bar 82 about its pivotal connection against the spring-actuated lever 97, so as to withdraw the projection 82^a to clear the pick-up dog 80, thus permitting the return spring 91 to restore the pick-up bar and the cross-totalizer 74 to their normal position. It will be seen that after the pick-up bar becomes released from the pick-up dog, the pick-up bar again swings upwardly until the pin 96 strikes the upper side of the slot 95^a on which it slides until the latter part of the return movement of the pick-up bar, at which time the latter is again swung downwardly by means of a cam 99 (Fig. 8) 130

on the pick-up bar, engaging with a cam 99^a on the portion 94 of the fixed bracket 95, thus bringing the pick-up bar to its normal depressed position to be engaged by the 5 next pick-up dog 80.

It will be seen that when one of the totalizers 51 is passing through a computing zone with the cross-totalizer 74, the back-spacer key 38 is effective, through the connections 10 hereinbefore described, to back-space the typewriter carriage 19, thus back-spacing the totalizer 51 and the cross-totalizer 74, which at this time is positively connected to the typewriter carriage by means of the 15 pick-up bar 82. It will be remembered that after the last digit is written in a computing zone, the cross-totalizer 74 becomes disconnected from the typewriter carriage and moves back to its normal position to the 20 right of the master wheel 66. As in my co-pending application, Serial No. 198,375, I have provided means actuatable by the back-spacer key 38 to reconnect the cross-totalizer 74 with the typewriter carriage, by means of 25 the pick-up bar 82, to bring the cross-totalizer into register denominational with the totalizer 51 when the latter is back-spaced after writing the last digit in a computing zone.

30 To reconnect the cross-totalizer 74 during a back-spacing operation of the carriage 19 to bring one of the totalizers 51 back into a computing zone, the back-spacer key 38, when depressed, pulls downwardly on a link 35 100 to swing an arm 101 extending from a short rock shaft 102, which may be mounted on a suitable bracket 103, secured to the machine frame. The forward end of the rock shaft 102 has a downwardly-projecting arm 40 104 to move a thrust link 105 laterally, so that an engaging portion 106 thereof, when the link 105 occupies its effective position, as shown in Fig. 5, engages with a pin 107 on a bell-crank 108 to swing the latter about 45 a fixed pivot 109 so as to draw on a link 110 connected to a branch 111 of the arm 89. This causes the rocking of the shaft 88 to move downwardly the free end of the arm 87, to draw the link 86 downwardly and 50 rock the bell-crank 83 about its pivot 84, thus moving the pick-up bar and consequently the cross-totalizer from the position indicated in Fig. 5 to that indicated in Fig. 6, where the pick-up bar has been reconnected 55 with the previously-engaged pick-up dog, and the cross-totalizer repositioned relatively to its master wheel.

From the foregoing, it will be understood that when the carriage is back-spaced, the 60 column-totalizer or traveling element 51 is back-spaced with respect to the master wheel or relatively-fixed element of the column-computing unit, and during this movement, which is caused by the back-spacer key 38, 65 the thrust bar 105 moves the cross-totalizer

or traveling element of the cross-computing unit from a normal retracted position to re-position it relatively to the master wheel or relatively-fixed element 66, thereby registering the two totalizers 51 and 74 denominational with respect to the master wheels 52 and 66, respectively. This operation also re-registers the cross-totalizer denominational relatively to the typewriter carriage. 70

In the present invention, provision is made for leaving the cross-totalizer 74 undisturbed during a back-spacing operation of the typewriter carriage, except when the latter is back-spaced into a computing zone 80 or while in a computing zone. To do this, I have found it advantageous to provide a break in the connections from the back-spacer key to the cross-totalizer, as at 106, 85 107. This break also permits the thrust bar 105 to be shifted, to render it effective, as will presently be described, so that the cross-totalizer may be repositioned thereby. To permit an actuation of the back-spacer key 38, without disturbing the cross-totalizer 74, 90 the thrust bar 105, which normally occupies the position indicated in Figs. 3 and 4, is provided with a cut-out or slot 112, which, when the cross-totalizer is in its normal position, is in alignment with the pin 107, as indicated in Fig. 4, so that the back-spacer key 38 may effect the back-spacing of the typewriter carriage, but the thrust link 105 will move idly over the pin 107, due to the cut-out 100 112.

The means for rendering the back-spacer key effective to position the cross-totalizer 74, or, in other words, the means for rendering the thrust link 105 effective, which is actuated by the back-spacer key, comprises 105 a lever 113, the forward end of which passes through a slot 114 in the thrust bar 105, which permits the latter to be moved independently of the lever 113. When the typewriter carriage is outside of a computing zone, the lever 113 occupies the position indicated in Figs. 1, 2 and 3, and is held in this position by a spring 116, to retain the thrust bar 105 ineffective. The spring pulls downwardly on one end of a pivoted lever or intermediate element 117 to swing the latter about its floating fulcrum 118 mounted on a swinging lever 119, to swing therewith about a pivot 120 on a bracket 121 secured to the machine frame. The tendency of the spring 116 to swing the lever 117 about its pivot tends to force downwardly a link 122 connected to the rear of the pivot lever 113, thus tending to hold the forward end thereof and consequently the free end of the thrust bar 105 115 120 in a raised position (Figs. 3 and 4).

The mechanism, including the lever 117, for raising or lowering the thrust bar 105 occupies an ineffective position when the typewriter carriage is outside of a comput- 130

ing zone, as indicated in Fig. 4. When, however, the carriage enters the computing zone, the pick-up dog 80 corresponding to the same position engages with a shoe 123, secured to the swinging lever 119 to swing the latter about its pivot 120, thus carrying therewith the fulcrum 118 to swing the free end of the pivoted lever 117 upwardly about its point of connection with the link 122 from the Fig. 4 to the Fig. 3 position. The shoe 123 is of such a length and in such a position as to be engaged by the pick-up dog when its associated totalizer enters a computing zone, and to hold the free end 10 of the pivoted lever 117 in the Fig. 3 position for one letter-space position beyond the digit of lowest denomination. The pick-up bar becomes released from the pick-up dog immediately after the digit of lowest 15 denomination is written, by means of the pin 96 which at this time engages with the cam 96^a, thus permitting the pick-up bar 82 to return to its normal position. During the latter part of the return movement of the 20 pick-up bar, a bent-off portion 124 thereof engages with an inclined face or cam 125 on the free end of the pivoted lever 117, to swing the latter about its pivot 118 and raise the connected end thereof to pull upwardly on the link 122, to swing the lever 113 about its fulcrum 115 and swing downwardly its forward end, thus carrying with it the free end of the thrust bar 105 to its effective position (Fig. 5), where the engaging portion 106 is in alinement or co-operative relation with the pin 107. The same condition will arise in case pick-up bar 82 becomes disconnected, accidentally or otherwise, from a dog 80 during the passage of 25 said dog through a computing zone. It will be seen that if the back-spacer key is now actuated, the typewriter carriage will be back-spaced, and that the cross-totalizer carriage will be reconnected therewith, (Fig. 30 6), as hereinbefore described. Thus, it will be understood that the means, comprising the intermediate lever 117, for rendering the thrust bar 105 effective is dependent for its effectiveness upon the position of the 35 carriage and is actuatable by the pick-up bar, which forms part of the train of mechanism extending between the cross-totalizer and the typewriter carriage.

Let it be assumed that the typewriter carriage has passed out of a computing zone, and the swinging lever 119 is in its lower position with the parts in the Fig. 4 position; if the carriage is now moved in a reverse letter-feed direction to a computing 40 zone, without the aid of the back-spacer key, the nearest pick-up dog or adjustable element 80 will engage with the shoe 123 to swing the lever 119 about its pivot, to swing the intermediate lever 117 about the bent-off portion 124 on the pick-up bar, which

at this time acts as a fulcrum for the intermediate lever. The intermediate lever pulls upwardly on the link 122 to render the thrust bar 105 effective, and at the same time lock the numeral keys against actuation, 70 as will presently be described. It will be seen that during this actuation of the intermediate element 117, it acts as a lever of the third order, the connection 118 to the swinging lever 119 acting as the point of 75 application therefor, and the pick-up bar 82, through the intermediary of the bent-off portion 124, acting as a fulcrum.

The numeral keys are locked to compel the operative to actuate the back-spacer key 80 38 when the typewriter carriage is moved back into a computing zone without the aid of the back-spacer key. For this purpose, I have provided, as in my co-pending application, Serial No. 198,375, an automatically-operated numeral-key lock. In the present invention, however, I preferably use the pivoted locking pawls 61, which are used to prevent the depression of another numeral key when a numeral key is in its actuated 90 position. It will be remembered that the pawls are suspended between two studs 64 with sufficient play therebetween to permit the entrance of the offset portion 60 of one of the pendants 59 between its associated 95 pawls. Thus, to lock the numeral keys when the typewriter carriage is backed into a computing zone, without the assistance of the back-spacer key, I have provided the lever 113 with a pendent link 126, having a rearward extension 127 thereon, which is forced 100 between two of the pawls 61 simultaneously with the rendering effective of the thrust bar 105 by an actuation of the lever 113, which is caused, for example, when the pick-up dog at the right-hand side of Fig. 4 is moved leftwardly (during a return movement of the typewriter carriage), thus raising the shoe 123 to raise the connected end 105 of the pivoted lever 117, through the intermediary of the fulcrum 118, the other end of the pivoted lever being at this time held by the overlying projection 124 (Fig. 5), which acts as a fulcrum for the lever 117. Any undue strain which may be caused when the overlying projection 124 acts as a fulcrum for the lever 117 is taken up by the offset 93, (Figs. 5 and 7), on the pick-up bar, which underlies the portion 94 of the fixed bracket 95 when the pick-up bar is in its normal or 115 retracted position.

It will be understood that the repositioning connections for the cross-totalizer and the key-lock are rendered effective simultaneously as the key-lock pendant 126 is connected to the lever 113, which renders the thrust bar 105, forming part of the connection from the back-spacer key, effective. As indicated in Fig. 5, letter-feeding movement 125 of the carriage from the last letter-space in 130

a computing zone to the first letter-space outside thereof will render effective the connections between the back-spacer key and the cross-totalizer and also the key-lock.

5 Further movement of the carriage in a letter-feeding direction by suitable means, such as an alphabet key or the space-bar, will release the lock.

To retain the thrust bar 105 in its effective relation with the pin 107 against the action of the return spring 116, during the actuation of the back-spacer key, there is provided an offset 130, Figs. 2 and 3, on the thrust bar 105, which moves under a retaining stud 131, secured to a suitable bracket 132 on the machine frame. This is found desirable, as, during the preliminary movement of the thrust bar 105, when actuated by the back-spacer key, the offset portion 124 of the pick-up bar moves out of engagement with the free end of the other pivoted pawl 117; at which time, without the aid of the retaining pin 131, the spring 116 would break the effective relation between 25 the thrust rod 105 and the stud 107 on the bell-crank 108.

It will be remembered that the shoe 123 will be retained effective in its upper or actuated position for one letter-space after the 30 last digit has been written in a computing zone, (Fig. 5.) It will also be seen that when the shoe 123 and the pick-up dog 80 occupy this relative position, the thrust bar 105 occupies its effective position. Thus, when the 35 back-spacer key 38 is actuated immediately after the writing of the last digit in a computing zone, it will be effective to reposition the cross-totalizer relatively to the typewriter carriage by back-spacing the typewriter carriage one letter-space and reconnecting the pick-up hook with the previously-engaged pick-up dog.

If the back-spacer key is actuated with the thrust bar 105 in its ineffective position, 45 Fig. 4, the offset portion 130 thereof will ride over the pin 131 to prevent the shifting of the thrust rod during its actuation by the back-spacer key. If the typewriter carriage, previous to the depression of the 50 back-spacer key, occupies a position with one of the pick-up dogs 80 immediately to the right of the shoe 123, indicated in dotted lines, (Fig. 4), the dog will, by the actuation of the back-spacer key, raise the shoe 55 to swing the lever 119, thus carrying with it the fulcrum 118, which, at this time, is effective to swing the intermediate lever 117 and cause an upward pull of the connecting link 122. It will also be remembered 60 that the thrust bar 105 is at this time riding over the pin 131; therefore, an independent movement of the link 122, relatively to the thrust bar 105, is permitted by providing a yielding connection between the connecting link 122 and the operating lever 113.

This connection may comprise a spring 133, one end of which is connected to the link 122, the other end being connected to the operating lever 113. The lower end of the connecting link 122 is provided with a slot 70 134 to permit this independent movement.

Variations may be resorted to within the scope of the invention, and portions of the improvements may be used without others.

Having thus described my invention, I 75 claim:

1. The combination with a typewriter carriage, of a cross-totalizer, means to cause said cross-totalizer to travel intermittently with said carriage, back-spacing means for 80 said carriage, and means for rendering said back-spacing means effective so that said cross-totalizer may be re-positioned thereby, relatively to said typewriter carriage.

2. The combination with a typewriter carriage, of a cross-totalizer, pick-up means, releasing means to cause said cross-totalizer to travel intermittently with said carriage, back-spacing means for said carriage, and means for rendering said back-spacing 90 means effective to re-position said cross-totalizer relatively to said typewriter carriage.

3. The combination with a typewriter carriage, of a plurality of column-totalizers 95 traveling therewith, a master wheel therefor, a cross-totalizer, a master wheel for said cross-totalizer, said cross-totalizer being adapted to travel with said typewriter carriage when one of the column-totalizers 100 passes through a computing zone, means to permit said cross-totalizer to return to its normal position when the typewriter carriage passes out of the computing zone, a back-spacer for said typewriter carriage, 105 and means for rendering said back-spacer effective, so that the cross-totalizer may be repositioned thereby relatively to its master wheel.

4. The combination with a carriage, of 110 a column-computer unit comprising two elements, namely, a master wheel and a totalizer, one of said elements traveling relatively to the other when said carriage passes through a computing zone, a cross-computer unit comprising two elements, namely, a master wheel and a totalizer, one of said last-mentioned elements being adapted to travel relatively to the other, means to cause the traveling element of said cross-computer 115 unit to travel with the traveling element of the column-computer unit, when the carriage passes through a computing zone, means to permit said cross-computer traveling element to return to a normal position 120 after the carriage passes out of the computing zone, a back-spacer for the traveling element of said column-computer unit, a connection from said back-spacer for causing a relative re-registering of the elements of 125 130

said cross-computer unit, and means for rendering said connection effective.

5. The combination with a typewriter carriage, of a cross-totalizer, pick-up devices on said typewriter carriage, a train of mechanism extending between the cross-totalizer and the typewriter carriage, said train of mechanism comprising a pick-up bar adapted to be engaged by one of said pick-up devices when the typewriter carriage enters a computing zone, means for releasing said pick-up bar from said pick-up device immediately after the carriage passes out of the computing zone, so as to permit the cross-totalizer to return to its normal position, a back-spacer key for said typewriter carriage, means actuatable by the back-spacer key for reconnecting said pick-up bar with said pick-up device, said means being normally ineffective, and means for automatically rendering said reconnecting means effective immediately after the typewriter carriage passes out of the computing zone.

6. The combination with a typewriter carriage, of a cross-totalizer carriage, a cross-totalizer thereon, pick-up means comprising a pick-up bar and releasing means to cause the cross-totalizer carriage to travel intermittently with said typewriter carriage, a back-spacer key, means actuatable by said back-spacer key to reconnect said cross-totalizer carriage with said typewriter carriage by means of said pick-up bar, so as to reposition the cross-totalizer denominational 35 relatively to said typewriter carriage, said repositioning means being normally ineffective, and means actuatable by said pick-up bar for rendering said repositioning means effective.

40 7. The combination with a typewriter carriage, of a cross-totalizer, means to cause the cross-totalizer to travel intermittently with said carriage, back-spacing means for said carriage, a broken connection between said carriage, a back-spacing means and said cross-totalizer carriage, and means for shifting said connection to render it effective to be actuated by the back-spacing means to reposition said cross-totalizer.

50 8. The combination with a typewriter carriage and a plurality of totalizers arranged to travel therewith, of a cross-totalizer, pick-up means and releasing means for causing the cross-totalizer to travel intermittently with said carriage, back-spacing means, and a connection from said back-spacing means for repositioning said cross-totalizer to register it denominational 55 with one of the totalizers on said typewriter carriage, said connection being at times ineffective when the cross-totalizer is in a normal position, so as to permit a back-spacing movement of the typewriter carriage without disturbing said cross-totalizer.

9. The combination with a typewriter carriage, of a cross-totalizer carriage, a cross-totalizer thereon, a train of mechanism extending between said cross-totalizer carriage and said typewriter carriage, pick-up devices and releasing means engaging with said train of mechanism to cause said cross-totalizer to travel intermittently with said typewriter carriage, a back-spacer key, and means actuatable by said train of mechanism after its release from said pick-up devices, for rendering said back-spacer key effective intermittently during the travel of said typewriter carriage, to reposition said cross-totalizer relatively to said typewriter carriage.

10. The combination with a typewriter carriage, of a cross-totalizer carriage, a cross-totalizer thereon, a train of mechanism, including a pick-up bar, extending between said cross-totalizer carriage and said typewriter carriage, pick-up devices and releasing means, engaging with said train of mechanism to cause said cross-totalizer to travel intermittently with said typewriter carriage, a back-spacer key, and means controlled by said pick-up devices and actuatable by said pick-up bar after its release from said pick-up devices for rendering said back-spacer key effective intermittently during the travel of the typewriter carriage to reconnect said cross-totalizer carriage with said typewriter carriage.

11. The combination with a typewriter carriage, of a plurality of adjustable devices arranged to travel therewith, a cross-totalizer, a train of mechanism extending between said cross-totalizer and said carriage, said train of mechanism engaging with said adjustable devices to cause said cross-totalizer to travel intermittently with said carriage, a back-spacer key, a connection from said back-spacer key, and means for automatically rendering said connection effective so that it may, when actuated by the back-spacer key, reposition the cross-totalizer.

12. The combination with a typewriter carriage and a plurality of totalizers arranged to travel therewith, of a cross-totalizer carriage, a cross-totalizer thereon, a train of mechanism extending between said cross-totalizer carriage and said typewriter carriage, means engaging with said train of mechanism to cause said cross-totalizer carriage to travel intermittently with said typewriter carriage, a back-spacer key, a connection from said back-spacer key, and means for intermittently rendering said connection effective so that it may, when actuated by the back-spacer key, engage with said train of mechanism to reconnect the cross-totalizer carriage with the typewriter carriage to re-register the cross-totalizer denominational 120 with one of the to- 130

talizers traveling with the typewriter carriage.

13. The combination with a typewriter carriage, of a cross-totalizer carriage, a cross-totalizer thereon, a train of mechanism extending between said typewriter carriage and said cross-totalizer carriage, pick-up dogs and releasing means, to cause said cross-totalizer carriage to travel intermittently with said typewriter carriage, back-spacing means for said typewriter carriage, and means for rendering said back-spacing means effective, so that the cross-totalizer carriage may be repositioned thereby, said rendering means being dependent for its effectiveness on the position of the typewriter carriage and actuatable by said train of mechanism.

14. The combination with a typewriter carriage, of a cross-totalizer carriage, a cross-totalizer thereon, back-spacing mechanism for said typewriter carriage, repositioning means for said cross-totalizer carriage actuatable by said back-spacing mechanism, means for rendering said repositioning means effective, said rendering means comprising a settable intermediate element which is set automatically to an effective position when the typewriter carriage enters a computing zone, and means for actuating said element in its set position, immediately after the typewriter carriage passes out of the computing zone, so as to render said repositioning means effective.

15. The combination with a typewriter carriage and a plurality of totalizers arranged at columnar positions on said typewriter carriage, of a cross-totalizer carriage, a cross-totalizer thereon, a train of mechanism comprising a pick-up bar, pick-up dogs arranged at columnar positions on said typewriter carriage corresponding with those of said totalizers, said pick-up dogs being adapted to engage with said pick-up bar at various positions in the travel of the typewriter carriage, a back-spacer key, and an element engaged by said pick-up dogs and actuated thereby to move an intermediate element, carried thereby, to an effective position, so that the pick-up bar upon its release, from a pick-up dog, is effective to actuate said intermediate element to render said back-spacer key effective to reconnect said cross-totalizer carriage with said typewriter carriage, to register the cross-totalizer denominational with one of the totalizers on said typewriter carriage.

16. The combination with a typewriter carriage, of a cross-totalizer, a train of mechanism extending from said cross-totalizer to a position adjacent said typewriter carriage, pick-up means for connecting said train of mechanism with said typewriter carriage to cause the cross-totalizer to travel with said typewriter

carriage, releasing means to render the pick-up means ineffective when the cross-totalizer has traveled through a computing zone, a back-spacer key, normally ineffective back-spacer-key-actuated means for repositioning said cross-totalizer, a controlling device for said normally ineffective means, and means for automatically operating said controlling device to render said normally ineffective means effective, so that said cross-totalizer may be positioned denominational relatively to the typewriter carriage by an actuation of the back-spacer key.

17. The combination with a typewriter carriage, of a cross-totalizer, means including a pick-up element to cause said totalizer to travel intermittently with said carriage, a back-spacer for said typewriter carriage, a normally ineffective connection from said back-spacer to reposition said cross-totalizer, and means including an intermediate element for rendering said connection effective, said intermediate element being actuatable by said pick-up element.

18. The combination with a typewriter carriage, of a plurality of adjustable elements traveling therewith, a cross-totalizer, means including a pick-up element to cause said totalizer to travel intermittently with said carriage, a back-spacer for said typewriter carriage, a normally ineffective connection from said back-spacer to reposition said cross-totalizer, and means including an intermediate element for rendering said connection effective, said intermediate element being actuatable by any one of said traveling elements when the typewriter carriage is moved in a reverse letter-feed direction.

19. The combination with a typewriter carriage, of a plurality of adjustable elements traveling therewith, a cross-totalizer, means including a pick-up element to cause said totalizer to travel intermittently with said carriage, a back-spacer for said typewriter carriage, a normally ineffective connection from said back-spacer to reposition said cross-totalizer, and means including an intermediate element for rendering said connection effective, said intermediate element being adapted to be actuatable by any one of said adjustable elements when the typewriter carriage is moved in a reverse letter-feed direction, said pick-up element at this time being relatively stationary, but assisting to effect the movement of said intermediate element.

20. The combination with a typewriter carriage, of a plurality of adjustable elements traveling therewith, a cross-totalizer, means including a pick-up element to cause said totalizer to travel intermittently with said carriage, a back-spacer for said typewriter carriage, a normally ineffective connection from said back-spacer to reposition said cross-totalizer, means including an in-

termediate element for rendering said connection effective, and a swinging element, said intermediate element being pivotally mounted on said swinging element, said adjustable elements engaging with said swinging element to move said intermediate element to an effective position to be actuated by said pick-up element upon the return movement of the latter to normal position, 10 thus rendering the connection from the back-spacer effective.

21. The combination with a typewriter carriage, of a plurality of adjustable elements traveling therewith, a cross-totalizer, 15 means including a pick-up element to cause said totalizer to travel intermittently with said carriage, a back-spacer for said typewriter carriage, a normally ineffective connection from said back-spacer to reposition 20 said cross-totalizer, means including an intermediate element for rendering said connection effective, and a swinging element, said intermediate element being pivotally supported thereon, said adjustable elements 25 engaging with said swinging element during a reverse letter-feed movement of the typewriter carriage to actuate said intermediate element, thereby rendering said connection from the back-spacer effective, the pick-up 30 element acting as a fulcrum for the intermediate element during its movement, while the pivot for said intermediate element on said swinging element acts as a point of application for the swinging element to move 35 said intermediate element.

22. The combination with a typewriter carriage, of a plurality of adjustable elements traveling therewith, a cross-totalizer, means including a pick-up element to cause 40 said totalizer to travel intermittently with said carriage, a back-spacer for said typewriter carriage, a normally ineffective connection from said back-spacer to reposition said cross-totalizer, means including an intermediate element for rendering said connection effective, a swinging lever, and a shoe on said swinging lever, said intermediate element being pivotally supported on 45 said swinging lever and settable to an effective position through the intermediary of said adjustable elements which engage with said shoe on said swinging lever, said intermediate element being actuatable as a lever of the first order by said pick-up element, to 50 render said connection from the back-spacer effective.

23. The combination with a typewriter carriage, of a plurality of adjustable elements traveling therewith, a cross-totalizer, 55 means including a pick-up element to cause said totalizer to travel intermittently with said carriage, a back-spacer for said typewriter carriage, a normally ineffective connection from said back-spacer to reposition 60 said cross-totalizer, means including an in-

termediate element for rendering said connection effective, a swinging lever, and a shoe on said swinging lever, said intermediate element being pivotally supported on said swinging lever, said adjustable elements 70 being effective during the movement of the carriage in the reverse letter-feed direction to actuate said intermediate element to render said connection from the back-spacer effective, said pivoted element, during its 75 actuation, serving as a lever of the third order, and said pick-up element serving at this time as a fulcrum for said pivoted element.

24. The combination with a typewriter carriage, of a plurality of pick-up devices traveling therewith, a cross-totalizer, means engaging with said pick-up devices to cause said cross-totalizer to travel intermittently with said carriage, back-spacing means for 85 said carriage, means actuatable by said back-spacing means to reconnect said cross-totalizer with a previously-engaged pick-up device, and means for retaining said reconnecting means in its effective position. 90

25. The combination with a typewriter carriage, of a cross-totalizer, means to cause said cross-totalizer to travel intermittently with said carriage, back-spacing means for said carriage, means actuatable by said back-spacing means to reposition said cross-totalizer relatively to said typewriter carriage, shifting means for said repositioning means, and means to prevent a shifting movement of said repositioning means during the actuation thereof by said back-spacing means. 100

26. The combination with a typewriter carriage, of a cross-totalizer, pick-up means and releasing means to cause said cross-totalizer to travel intermittently with said carriage, back-spacing means for said carriage, means actuatable by said back-spacing means to reposition said cross-totalizer relatively to said typewriter carriage, a spring for retaining said repositioning means in 110 an ineffective position, means for rendering said repositioning means effective, and means for retaining said repositioning means in its effective position against the action of said spring, during the actuation 115 of said repositioning means by said back-spacing means.

27. The combination with a typewriter carriage, of a plurality of pick-up devices traveling therewith, a cross-totalizer, means 120 engaging with said pick-up devices to cause said cross-totalizer to travel intermittently with said carriage, a back-spacer for said carriage, repositioning means, for said cross-totalizer, comprising a normally ineffective 125 connection from said back-spacer, means including an intermediate element for rendering said repositioning means effective, and a yielding connection between said intermediate element and said repositioning means, 130

to permit an actuation of said intermediate element without effecting said repositioning connection.

28. The combination with a typewriter carriage, of a plurality of adjustable devices arranged to travel therewith, a cross-totalizer carriage, a cross-totalizer thereon, a train of mechanism comprising a connecting member extending from said cross-to-talizer carriage and engaging individually with said adjustable devices, so as to cause said cross-totalizer to travel intermittently with said typewriter carriage, a back-spacer key for said typewriter carriage, a normally ineffective connection from said back-spacer key to reposition said cross-totalizer relatively to the typewriter carriage by reconnecting said train of mechanism with the previously-engaged adjustable device, means for rendering said connection effective, said connection comprising a pivoted element, and means controlled by said adjustable devices to render said pivoted element effective, said connecting member being effective after its release from one of the adjustable devices to actuate said pivoted element, thereby rendering said repositioning means effective.

29. The combination with a typewriter carriage, of a cross-totalizer carriage, a cross-totalizer thereon, a train of mechanism comprising a pick-up bar extending between said cross-totalizer and said typewriter carriage, dogs on said typewriter carriage adapted to engage individually with said pick-up bar at various intervals during the travel of the typewriter carriage, means for releasing said pick-up bar from said dogs, to permit the cross-totalizer to return to its normal position immediately after the typewriter carriage passes out of the computing zone, a back-spacer key for said typewriter carriage, a connection from said back-spacer key, normally ineffective, for reconnecting said pick-up bar with the previously-engaged dog, means for rendering said connection effective, said means comprising a pivoted element, means for rendering said pivoted element effective, and means on said pick-up bar for actuating said pivoted element to render said connection effective by the return movement of said pick-up bar.

30. The combination with a typewriter carriage, of a cross-totalizer carriage, a cross-totalizer thereon, a train of mechanism comprising a pick-up bar extending between said cross-totalizer and said typewriter carriage, pick-up dogs on said typewriter carriage, adapted to engage individually with said pick-up bar at various positions during the travel of the typewriter carriage, means for releasing said pick-up bar from said dogs, to permit the cross-totalizer to return to its normal position immediately after

the typewriter carriage passes out of a computing zone, a back-spacer key for said typewriter carriage, a connection from said back-spacer key, normally ineffective, for reconnecting said pick-up bar with the previously-engaged dog, means for rendering said normally ineffective connection effective, said means comprising a pivoted element, means for rendering said pivoted element effective, means on said pick-up bar for actuating said pivoted element to render said connection effective by the return movement of said pick-up bar, and means for retaining said connection in its effective position during an actuation thereof, so that the pick-up bar may move out of engagement with the pivoted element to be reconnected with one of said dogs.

31. The combination with a typewriter carriage, of a plurality of adjustable pick-up devices arranged at columnar positions of said carriage, a cross-totalizer, means engaging with said adjustable devices to cause said cross-totalizer to travel intermittently with said typewriter carriage, back-spacing means for said carriage, and means effective, when said carriage is backed to bring a columnar position thereof to the printing point to render said back-spacing means effective, so that it may, when actuated, reconnect said cross-totalizer with the previously-engaged adjustable device.

32. The combination with a typewriter carriage, of a cross-totalizer, means to cause the cross-totalizer to travel intermittently with said carriage, back-spacing means for said carriage, and means controlled by said carriage when it is backed into a computing zone to render said back-spacing means effective to reposition said cross-totalizer relatively to said typewriter carriage.

33. The combination with a typewriter carriage, of a cross-totalizer, means to cause the cross-totalizer to travel intermittently with said carriage, back-spacing means for said carriage, means controlled by the typewriter carriage when it is backed, substantially into a computing zone, to render said back-spacing means effective, to reposition said cross-totalizer relatively to said typewriter carriage, numeral keys, and means for rendering said numeral keys ineffective when said carriage is moved, as above stated, without the aid of the back-spacing means.

34. The combination with a typewriter carriage, of a cross-totalizer, means to cause the cross-totalizer to travel intermittently with said carriage, back-spacing means for said carriage, means controlled by the typewriter carriage, when it is backed substantially into a computing zone, to render said back-spacing means effective to reposition said cross-totalizer relatively to said typewriter carriage, numeral keys, normally ineffective locking means for said numeral

keys, and means for rendering said locking means effective when the carriage is moved, as above stated.

35. The combination with a typewriter carriage, of a cross-totalizer, means to cause the cross-totalizer to travel intermittently with said carriage, back-spacing means for said carriage, means controlled by the typewriter carriage, when it is backed substantially into a computing zone, to render said back-spacing means effective to reposition said cross-totalizer relatively to said typewriter carriage, numeral keys, means for rendering said numeral keys ineffective when said carriage is moved, as above stated, without the aid of said back-spacing means, and means for rendering said keys effective.

36. The combination with a typewriter carriage, of a cross-totalizer, means to cause the cross-totalizer to travel intermittently with said carriage, a back-spacer key for said carriage, means controlled by the typewriter carriage, when it is backed substantially into a computing zone, to render said back-spacer key effective to reposition said cross-totalizer relatively to said typewriter carriage, numeral keys, and normally ineffective locking means for said numeral keys, rendered effective when said back-spacer key is rendered effective for repositioning the cross-totalizer, said locking means being rendered ineffective again when said back-spacer key is actuated.

37. The combination with a typewriter carriage, of a plurality of adjustable elements traveling therewith, a cross-totalizer, means including a pick-up element to cause said totalizer to travel intermittently with said carriage, a back-spacer for said typewriter carriage, a connection from said back-spacer to reposition said cross-totalizer, numeral keys, locking means for said numeral keys, and means including an intermediate element for rendering said locking means effective, said intermediate element being actuatable by any one of said adjustable elements when the typewriter carriage is moved in a reverse letter-feed direction into a computing zone, said pick-up element at this time being relatively stationary, but assisting to effect the movement of said intermediate element.

38. The combination with a typewriter carriage, of a cross-totalizer, means to cause said cross-totalizer to travel intermittently with said carriage, back-spacing means for said carriage, numeral keys, locking means for said numeral keys, a normally ineffective connection from said back-spacing means to reposition said cross-totalizer, and means for simultaneously rendering said connection and said locking means effective.

39. The combination with a typewriter carriage, of a cross-totalizer, means to cause the cross-totalizer to travel intermittently

with said carriage, back-spacing means for said carriage, numeral keys, locking means for said numeral keys, a normally ineffective connection from said back-spacing means to reposition said cross-totalizer and means, rendered effective by the typewriter carriage when the latter is backed substantially into a computing zone, for simultaneously rendering said connection and said locking means effective and for retaining said locking means effective if the carriage is moved, as above stated, without the aid of said back-spacing means.

40. The combination with a typewriter carriage, of a cross-totalizer, means including a pick-up element for causing said cross-totalizer to travel intermittently with said carriage, a back-spacer for said carriage, a normally ineffective connection from said back-spacer to reposition said cross-totalizer, numeral keys, locking means for said numeral keys, and an intermediate element, actuatable by said pick-up element, to simultaneously render said connection and locking means effective.

41. The combination with a typewriter carriage, of a plurality of adjustable elements traveling therewith, a cross-totalizer, means including a pick-up element for causing said cross-totalizer to travel intermittently with said carriage, a back-spacer for said carriage, a normally ineffective connection from said back-spacer to reposition said cross-totalizer, numeral keys, locking means for said numeral keys, and an intermediate element actuatable by any one of said traveling elements, when the typewriter carriage is moved in a reverse letter-feed direction to simultaneously render said connection and said locking means effective.

42. The combination with a typewriter carriage, of a plurality of adjustable elements traveling therewith, a cross-totalizer, means including a pick-up element to cause said cross-totalizer to travel intermittently with said carriage, a back-spacer for said carriage, a normally ineffective connection from said back-spacer to reposition said cross-totalizer, numeral keys, locking means for said numeral keys, means including an intermediate element for simultaneously rendering said connection and said locking means effective, a swinging lever, and a shoe on said swinging lever, said intermediate element being pivotally supported on said swinging lever and being settable to an effective position through the intermediary of said adjustable elements which engage with said shoe on said swinging lever, said pivoted element being actuatable as a lever of the first order by said pick-up element to simultaneously render said connection and said locking means effective.

43. The combination with a typewriter carriage, of a cross-totalizer, means to cause

said cross-totalizer to travel intermittently with said carriage, a back-spacer key for said carriage, numeral keys, locking means for said numeral keys, a normally ineffective connection from said back-spacer key to reposition said cross-totalizer, means rendered effective by said typewriter carriage when the latter is backed substantially into a computing zone, for simultaneously rendering said connection and said locking means effective and for retaining said locking means effective when the carriage is so moved without the aid of said back-spacer key, and means controlled by said back-spacer key to release said locking means.

44. The combination with a typewriter carriage, of a cross-totalizer carriage, a cross-totalizer thereon, a train of mechanism, means engaging with said train of mechanism to cause said cross-totalizer to travel intermittently with said typewriter carriage, said train of mechanism comprising a pick-up bar pivotally connected to a bell-crank, said bell-crank being connected to rock a shaft by an arm extending therefrom, said shaft having another arm connected to said cross-totalizer carriage, and a return spring for said train of mechanism.

45. The combination with a typewriter carriage, and of a cross-totalizer carriage, a cross-totalizer thereon, a train of pick-up mechanism extending between said cross-totalizer carriage and said typewriter carriage, said pick-up mechanism comprising a pick-up bar pivotally mounted on a rock-arm, said rock-arm being connected through intermediate mechanism to one end of a rockshaft, an arm rigidly secured to the other end of said rockshaft, said two arms moving in parallelism, and a link connecting said last-mentioned arm with said cross-totalizer carriage.

46. The combination with a typewriter carriage, of a cross-totalizer carriage, a cross-totalizer thereon, a train of pick-up mechanism extending between said cross-totalizer carriage and said typewriter carriage, said pick-up mechanism comprising a pick-up bar pivotally mounted on a bell-crank, a second bell-crank connected to move in parallelism with said first-mentioned bell-crank, a link connecting said second-mentioned bell-crank with said cross-totalizer, and a return spring for said mechanism.

47. The combination with a typewriter carriage, of a cross-totalizer carriage, a cross-totalizer thereon, a train of mechanism comprising a bell-crank extending between said cross-totalizer carriage and said typewriter carriage, an actuating element connected to said bell-crank, a back-spacer key, a normally ineffective connection from said back-spacer key, and means for render-

ing said connection effective, so that it may engage with said actuating element to reposition said cross-totalizer relatively to said typewriter carriage.

48. The combination with a main carriage, of a sub-carriage, means to cause said sub-carriage to travel intermittently with said main carriage, back-spacing means for said main carriage, and means for rendering said back-spacing means effective so that said sub-carriage may be repositioned relatively to said main carriage.

49. The combination with a main carriage and a plurality of adjustable devices arranged thereon, of a sub-carriage, a train of mechanism extending between said sub-carriage and said main carriage, said train of mechanism engaging with said adjustable devices to cause said sub-carriage to travel intermittently with said main carriage, a back-spacer key, a connection from said back-spacer key, and means for automatically rendering said connection effective so that it may, when actuated by the back-spacer key, reposition the sub-carriage relatively to said main carriage.

50. The combination with a main carriage and a plurality of pick-up devices thereon, of a sub-carriage, means engaging with said pick-up devices to cause said sub-carriage to travel intermittently with said main carriage, back-spacing means for said main carriage, means actuatable by said back-spacing means to reconnect said sub-carriage with a previously-engaged pick-up device, and means for retaining said reconnecting means in its effective position.

51. The combination with a main carriage and a plurality of adjustable devices thereon, of a sub-carriage, a train of mechanism comprising a connecting member extending from said sub-carriage and engaging individually with said adjustable devices, releasing means for said connecting member to cause said sub-carriage to travel intermittently with said main carriage, a back-spacer key for said main carriage, a normally ineffective connection from said back-spacer key to reposition said sub-carriage relatively to the main carriage by reconnecting said train of mechanism with the previously-engaged adjustable device, means to render said connection effective, said connection comprising a pivoted element, and means controlled by said adjustable devices for rendering said pivoted element effective, said connecting member being effective after its release from one of the adjustable devices to actuate said pivoted element, thereby rendering said connection effective.

52. The combination with a main carriage and a plurality of adjustable devices arranged at columnar positions thereon, of

a sub-carriage, means to cause said sub-carriage to travel intermittently with said main carriage, back-spacing means for said main carriage, and means, effective when 5 said main carriage is backed to bring a columnar position thereof to the printing point, to render said back-spacing means effective, so that it may, when actuated, reconnect said sub-carriage with the previous 10ously-engaged adjustable device.

53. The combination with a main carriage, of a sub-carriage, means to cause the sub-carriage to travel intermittently with said main carriage, back-spacing means for 15 said main carriage, means controlled by the main carriage, when it is moved back to bring a columnar position to the printing point, to render said back-spacing means effective to reposition said sub-carriage relatively to said main carriage, numeral keys, and means for rendering said numeral keys ineffective when said main carriage is moved, as above stated, without the aid of said back-spacing means.

20 54. The combination with a main carriage, of a sub-carriage, means to cause said sub-carriage to travel intermittently with said main carriage, back-spacing means for said main carriage, numeral keys, locking means for said numeral keys, a normally-ineffective connection from said back-spacing means to reposition said sub-carriage, and means for simultaneously rendering said connection and said locking 35 means effective.

55. The combination with a main carriage, of a sub-carriage, means including a pick-up element for causing said sub-carriage to travel intermittently with said 40 main carriage, a back-spacer for said main carriage, a normally-ineffective connection from said back-spacer to reposition said sub-carriage, numeral keys, locking means for said numeral keys, and means including 45 an intermediate element for simultaneously rendering said connection and said locking means effective, said intermediate element being actuable by said pick-up element.

56. The combination with a main carriage, of a plurality of adjustable elements thereon, a sub-carriage, means including a pick-up element to cause said sub-carriage to travel intermittently with said main carriage, a back-spacer for said main carriage, 55 a normally ineffective connection from said back-spacer to reposition said sub-carriage, numeral keys, locking means for said numeral keys, means including an intermediate lever for simultaneously rendering 60 said connection and said locking means effective, a swinging lever, and a shoe on said swinging lever, said intermediate lever being pivotally supported on said swinging lever and being settable to an effective position through the intermediary of said ad-

justable elements which engage with said shoe on said swinging lever, said pivoted lever being actuatable as a lever of the first order by said pick-up element to simultaneously render said connection and said locking means effective. 70

57. The combination with printing mechanism, including a traveling carriage and numeral keys, of a cross-totalizer, means to cause said cross-totalizer to move with said traveling carriage through a computing zone and to be released when said carriage passes out of said zone, means to return said cross-totalizer to its normal position, a lock normally effective to prevent simultaneous depression of more than one numeral key, and means whereby, upon disconnection of said cross-totalizer from said traveling carriage, while the latter is in a computing zone, said numeral-key-lock will 80 be rendered effective to prevent the depression of any of said numeral keys. 85

58. The combination with printing mechanism, including a traveling carriage and numeral keys, of a cross-totalizer, means to cause said cross-totalizer to move with said traveling carriage through a computing zone and to be released when said carriage passes out of said zone, means to return said cross-totalizer to its normal position, 90 a lock normally effective to prevent simultaneous depression of more than one numeral key, means whereby, upon disconnection of said cross-totalizer from said traveling carriage, while the latter is in the 95 computing zone, said numeral-key-lock will be rendered effective to prevent the depression of any of said numeral keys, and means to restore said numeral-key-lock to its normal condition. 100

59. The combination with printing mechanism, including a traveling carriage and numeral keys, of a cross-totalizer, means to move said totalizer through a computing zone with said carriage and to return the same to normal position, a numeral-key-lock normally permitting the depression of only one key at a time, means effective when said cross-totalizer becomes released from its moving means, while passing through a computing zone, to render said lock effective to prevent the depression of any of said numeral keys, and means to restore said cross-totalizer to the control of said moving means and to restore said numeral-key-lock to normal 110 condition. 115

60. The combination with printing mechanism, including a traveling carriage and numeral keys, of a cross-totalizer, means to move said totalizer through a computing zone with said carriage and to return the same to normal position, a numeral-key-lock normally permitting the depression of only one key at a time, means rendered effective 125 when the traveling carriage passes out of 130

- the computing zone for said cross-totalizer, to render said lock effective to lock all of said numeral keys, and means to release said lock.
- 5 61. The combination with printing mechanism, including a traveling carriage and numeral keys, of a cross-totalizer, means to move said totalizer through a computing zone with said carriage and to return the 10 same to normal position, a numeral-key-lock normally permitting the depression of only one key at a time, means actuated by said cross-totalizer, when returned to its normal position after passage through the computing 15 zone, for rendering said numeral-key-lock effective to prevent the depression of any of said numeral keys, and means to restore said numeral-key-lock to its normal condition.
- 20 62. The combination with a typewriter carriage, of a cross-totalizer, means including a pick-up element to cause said totalizer to travel intermittently with said carriage, a back-spacer for said typewriter carriage, 25 a connection from said back-spacer to reposition said cross-totalizer, numeral keys, locking means for said numeral keys normally permitting the depression of only one of them at a time, and means including an 30 intermediate element for rendering said locking means effective, said intermediate element being actuatable by said pick-up element.
63. The combination with a typewriter carriage and a plurality of adjustable elements traveling therewith, of a cross-totalizer, means including a pick-up element to cause said totalizer to travel intermittently with said carriage, a back-spacer for said typewriter carriage, a connection from said back-spacer to reposition said cross-totalizer, numeral keys, locking means for said numeral keys, means including an intermediate element for rendering said locking 35 means effective, and a swinging element, said intermediate element being pivotally-mounted on said swinging element, said adjustable elements engaging with said swinging element to move said intermediate element to an effective position to be actuated by said pick-up element during the return movement of the latter to normal position, thus rendering the said locking means effective.
- 40 64. The combination with a typewriter carriage and a plurality of adjustable elements traveling therewith, of a cross-totalizer, means including a pick-up element to cause said totalizer to travel intermittently with said carriage, a back-spacer for said typewriter carriage, a connection from said back-spacer to reposition said cross-totalizer, numeral keys, locking means for said numeral keys, means including an intermediate 45 element for rendering said locking means effective, and a swinging element, said intermediate element being pivotally-supported thereon, said adjustable elements engaging with said swinging element during a reverse letter-feed movement of the typewriter carriage to actuate said intermediate element, thereby rendering said locking means effective, the pick-up element acting as a fulcrum for the intermediate element during its movement, while the pivot for said intermediate element on said swinging element acts as a point of application for the swinging element to move said intermediate element.
- 50 65. The combination with a typewriter carriage and a plurality of adjustable elements traveling therewith, of a cross-totalizer, means including a pick-up element to cause said totalizer to travel intermittently with said carriage, a back-spacer for said typewriter carriage, a connection from said back-spacer to reposition said cross-totalizer, numeral keys, locking means for said numeral keys, means including an intermediate lever for rendering said locking means effective, a swinging lever, and a shoe on said swinging lever, said intermediate lever being pivotally-supported on said swinging lever and settable to an effective position through the intermediary of said adjustable elements which engage with said shoe on said swinging lever, said pivoted lever being actuatable as a lever of the first order by said pick-up element, to render said locking means effective.
- 55 66. The combination of typewriting mechanism, including a traveling carriage and numeral keys, of computing mechanism operated by said numeral keys, comprising a cross-totalizer, means to move said cross-totalizer through a computing zone with said carriage and to return it to normal position, means actuated by said cross-totalizer, when released by the passage of the typewriter carriage out of the computing zone, to prevent printing of numerals in the first letter-space following a computing zone, and means to release said preventing means.
- 60 67. The combination of typewriting mechanism, including a traveling carriage and numeral keys, of computing mechanism operated by said numeral keys, comprising a cross-totalizer, means to move said cross-totalizer through a computing zone with said carriage and to return it to normal position, numeral-key-locking means normally permitting the depression of only one of said keys at a time, and means whereby said locking means may be made effective to lock all of said numeral keys upon passage of said traveling carriage into a computing zone.
- 65 68. The combination with typewriting mechanism, including a traveling carriage

and numeral keys, of computing mechanism operated by said numeral keys, comprising a cross-totalizer, means to connect said cross-totalizer with said traveling carriage 5 to travel therewith into a computing zone, and to disconnect said cross-totalizer from said carriage when the traverse of a computing zone has been completed, means to return said cross-totalizer to its normal position, a numeral-key-lock normally permitting the depression of only one of said keys at a time, and means controlled jointly by said traveling carriage and said cross-totalizer, when disconnected, to render said numeral-key-lock effective to prevent depression of any of said numeral keys.

69. In a computing machine, the combination with a traveling carriage, of a cross-totalizer, means, including a pick-up device, 20 to cause said cross-totalizer to travel with the carriage through a computing zone and to release said cross-totalizer, a back-space mechanism, including a back-space key, a reciprocable link, back-space-key-actuated 25 means connected with said link at one end to reciprocate the same, means to move said cross-totalizer from its normal position to render the pick-up device effective when the carriage is in a computing zone, including 30 a member to be engaged by said link, means, including a spring, for normally maintaining the free end of said link in such a position that, when actuated, its free end will pass to one side of said member, yielding 35 means to overcome said spring and position the free end of said link for engagement with said member, and means for preventing the free end of said link from being shifted in either direction during the action of said 40 back-space key.

70. The combination with typewriting mechanism, including a traveling carriage, keys, including numeral keys, key-controlled means for effecting letter-space movements

of said carriage, and back-spacer means, including a back-space key, of numeral-key-controlled computing means, including a cross-totalizer, means for connecting said cross-totalizer to said traveling carriage to travel therewith through a computing zone, 50 means to render said connecting means ineffective when the carriage passes out of the computing zone, means for locking said numeral keys against depression, said locking means being rendered effective when said carriage is either advanced or backed into the first letter-space position outside of the computing zone, and being released when the carriage is fed into the next letter-space position, and means whereby actuation of the back-space key, to effect movement of the carriage from the first letter-space position outside of the computing zone into the last letter-space position in the computing zone, will reconnect said cross-totalizer with said carriage and render said numeral-key-locking means ineffective.

71. The combination with a typewriter carriage and numeral keys, of a cross-totalizer, means to cause the cross-totalizer to travel intermittently with said carriage, back-spacing means for said carriage, means for locking said numeral keys, a normally ineffective device whereby actuation of said back-spacing means may advance said cross-totalizer from its ineffective position to cause it to be connected with said carriage, means whereby backing of said carriage into a computing zone, without the aid of said back-spacing means, may render said device effective, and means whereby said locking means will be rendered effective when said device is effective.
